DIFFERENTIAL HEATING SYSTEM

Original Filed April 4, 1924

UNITED STATES PATENT OFFICE

CLAYTON A. DUNHAM, OF GLENCOE, ILLINOIS, ASSIGNOR TO C. A. DUNHAM COMPANY, OF MARSHALLTOWN, IOWA, A CORPORATION OF IOWA

DIFFERENTIAL HEATING SYSTEM

Original application filed April 4, 1924, Serial No. 704,142. Renewed November 9, 1927. Divided and this application filed December 31, 1927, Serial No. 243,861. Renewed April 22, 1929.

This invention relates to a steam heating system, comprising separate supply and return mains, and adapted to normally supply steam at sub-atmospheric pressures to the radiators. Means are provided for maintaining the required vacuum or low pressure in the return main, as well as a certain pressure differential between the supply and return mains. This exhausting mechanism withdraws only air and non-condensable gases, the condensate which accumulates in the return main gravitating directly to the boiler or steam generator. According to the present invention, a return-trap is provided in the return main, where steam pressure is automatically provided, if necessary, to assist the head of water in the return main in returning the accumulated liquid condensate to the boiler. This application is a division of my copending application, Serial No. 704,142, filed April 4, 1924.

The principal object of the invention is to provide a new and improved combination of parts adapted to carry out the principles of this invention as briefly outlined hereinabove, and as explained in detail in the description which follows.

Other objects and advantages of this invention will be more apparent from the following detailed description of one approved form of the apparatus.

In the accompanying drawings:

Fig. 1 is a diagrammatic elevation of the assembled apparatus.

Fig. 2 is a vertical section through one of the radiator inlet valves.

Referring to the drawings A designates one of the radiators of the heating system, and B is the steam supply main opening out of the steam space of the steam generator or boiler C and connected by a supply pipe D with radiator A. A manually controlled inlet valve E limits the supply of steam admitted from pipe D to radiator A, and F is a steam trap of any preferred construction, preferably of the expansible fluid-filled disk type, located at the outlet of the radiator. This trap is connected by a pipe 1 with the return main G. It is to be understood that the

similar radiators that may be utilized in the system, each radiator being provided with a supply pipe D and a return pipe 1, another pair of these pipes being indicated at the left of the drawing.

As shown particularly in Fig. 2, the inlet valve E comprises a casing 43 having an inlet port 44 communicating with supply pipe D and adapted to be closed by a valve 45 arranged on a structure 46 having a stem 47 provided on opposite sides with notches 48 for non-rotatable engagement with the nut 31 which has threaded engagement with an internally threaded sleeve 32 adapted to be rotated by a handle 33, the sleeve and handle being supported by the bonnet 34 of the valve casing. The stem 47 is non-circular in cross-section and extends through an opening of similar shape in a guide plate 35 which is interposed between the upper edge of the casing and the bonnet. Consequently when the handle 33 is turned, nut 31 is forced downwardly so as to seat the valve 45 over port 44. The outlet port of the valve casing is through a boss 36 secured by union 37 to a nipple 38, which is screwed into radiator A. A plate or disc 39 formed with an orifice 40 is arranged in the boss 36 and is held against a shoulder 41 by a split ring 42. The orifice plate 39 is removable, so that the valve for each of the radiators of the heating system may be fitted with a plate having an orifice of the proper size to provide for the admission to the radiator of the proper amount of steam. The orifices are of such size that when the system is filled with steam, they will admit enough steam to the radiators to make up for condensation. That is, the pressure in the radiators will substantially equal the supply pipe pressure. The orifice plates function to restrict the flow of steam when the system is started up, so that they insure the full supply of steam to the radiators remote from the generator.

The return main G is connected with the boiler of generator C below the water level therein and is provided with a check valve 2 opening towards the boiler. A drip-pipe H connects the end of the steam supply main B with return main G between the check valve 2 and the boiler C.

valve 2 and the boiler. At I is shown a thermostatic trap positioned in a pipe 3 between the drip pipe H and the return main G for venting air from the drip pipe into the return main. At J is an air eliminator connected by pipe 4 with the return main, and having an air outlet pipe 5 provided with an outwardly opening check valve 6. At K is shown a thermostat, preferably, but not necessarily, employed for controlling the dampers 7 and 8 of the steam generator through the instrumentality of a damper operating motor 9 of common construction.

Liquid condensate is returned to the boiler from return main G and drip pipe H by gravity, as hereinafter described. The air and non-condensable gases are withdrawn from the return main G through a pipe 10 leading to any suitable type of exhausting apparatus, the one here indicated being disclosed and described more in detail in my parent application Serial No. 704,142, hereinabove referred to. At L is indicated a hurling water tank connected by pipe 11 with the drip pipe H. The water level in drip pipe H will normally extend above the pipe 11, so that a constant supply of water is maintained in the tank L. However, the same water is used over and over again in this pumping system, being withdrawn from and returned to the tank L, so that there is normally no appreciable flow of liquid through the pipe 11. The centrifugal pump M receives water from tank L and forces the same through a jet exhauster N, to the suction space of which is connected the pipe 10, leading from the return main G, this pipe being provided with a check valve 12 opening toward the jet exhauster. Water from the jet exhauster passes into an air separating tank O and thence back to the water tank L. The air and gases are discharged to the atmosphere from tank O through a float-controlled valve, the outlet also being provided with an outwardly opening check-valve. All of this is disclosed more in detail in my co-pending application, Serial No. 704,142, above referred to. This form of pumping or exhausting mechanism is here shown merely by way of example, and many other forms of motor-driven or other suitable exhausting mechanism could be substituted for the one here illustrated diagrammatically.

The pump M is preferably driven by an electric motor P, the controlling switch Q of which is governed by a differential pressure device R, the low pressure chamber of which is connected by pipe 19 with pipe 10 leading from the return main G, and the high pressure chamber of the controller is connected by means of pipe 20 with some portion of the system which is substantially at boiler pressure. As here shown, pipe 20 connects into the hurling water circuit.

The exhausting mechanism operates to

withdraw air (which term is intended to include also non-condensable gases) from the return main of the heating system, and to vent this air. The control mechanism is so adjusted that the exhausting means will continue to operate until a predetermined difference in pressure has been established between the return main G and the supply main B (that is all parts of the system which are at substantially boiler pressure), after which the differential controller R will operate the switch Q to shut off motor P thus stopping the pumping system. When this pressure differential has fallen below the desired minimum the exhausting mechanism will again be automatically started to renew the withdrawal of gases from the return main G.

The horizontal leg 21 of the return main G is considerably above the water line of the boiler so that water of condensation from the heating system will flow into the boiler of the generator by gravity due to the hydrostatic head of water collecting in the vertical leg or standpipe 22 of the return main above the boiler water level, so long, that is, as the boiler pressure is effectively less than the force exerted by such water column. The return main is shut off from boiler pressure by check valve 2. The accumulation of water in the drip pipe H will continue until this water balances the boiler pressure, after which the excess water accumulation will flow by gravity into the boiler.

At the top of the vertical leg 22 of return main G is positioned a return trap T, into which the horizontal leg 21 of the return main discharges. The return pipe 21 is provided with a one-way check valve 23, opening toward the trap T, and preferably the pipe 21 is provided with a downwardly bent portion 24 to overcome the resistance of valve 23 to the water accumulation behind the valve. The trap is in open communication with the vertical leg 22 of return main G. The return trap T is of a type in common use, the one here shown by way of example being disclosed in the patent to Johnson, 1,509,299, granted September 23, 1924. Any other trap of this general type might be used in place of that here shown. The trap T has an air vent pipe 25 leading to the atmosphere and provided with an outwardly opening check valve 26.

A pipe 27 connects the trap with the steam supply main B. The openings between the trap and the pipes 25 and 27 are provided with valves under control of a pivoted float 28. When the float is down, that is when there is no material accumulation of water in the tank T, the steam pipe 27 will be closed and the air vent pipe 25 will be open. When sufficient water has accumulated in the trap to raise the float a predetermined distance, the valve controlling the air vent pipe is closed and the valve controlling the steam

pipe opened so that steam pressure is exerted on the water in the trap thus balancing boiler pressure and the water will flow by gravity into the boiler.

5 An equalizing pipe 29 connects the vent pipe 25 with the air eliminator J, this pipe 29 being provided with a one-way check valve 30 which opens towards the air eliminator.

When starting the operation of this system, 10 the thermostatic traps F will be open (there being no steam in the radiators) and if current is available to operate the pump motor the exhausting mechanism will function since there will be no pressure differential between the 15 supply and return mains at this time. Air will be exhausted from the return main G, and also through main G from the entire system since the traps F are open, and the lowered pressure in the boiler will cause steam 20 to be supplied to the radiators at a lower temperature than if the boiler were subject to atmospheric pressure. When the radiators A have filled with steam, the traps F will 25 close. The exhausting mechanism will continue to operate until the return main G (now 30 shut off from the supply side of the system) is further exhausted and the desired pressure differential has been established between the supply and return sides of the system, whereupon the differential controller R will function 35 to stop the exhausting mechanism. As the steam in the radiators A condenses, the water will flow into the traps F thus causing these traps to open and permit the water to 40 flow through pipes 1 to the return main G, the trap F immediately closing as soon as steam attempts to pass therethrough. The vacuum created by the condensing steam in the radiators will act to maintain a sub-atmospheric pressure in the radiators, and by 45 suitably controlling the fires in steam generator C any desired sub-atmospheric pressure of the steam within the radiators may be maintained, thus varying the heat given out by the radiators in accordance with temperature requirements.

The water of condensation will gravitate 50 into the vertical leg 22 of the return main G and will accumulate until the column of water in pipe 22 stands above the water level in the boiler to an extent sufficient to overbalance the boiler pressure, whereupon the excess head of water will open the one-way valve 2 and gravitate into the boiler. Water of condensation 55 will also accumulate in the drip pipe H (which is at boiler pressure) until the head of water in this pipe is sufficient to force the excess water into the boiler against the boiler pressure. Water will accumulate to a height 60 slightly above the pipe 11, so that the exhausting mechanism will always be primed. Any air accumulating in drip pipe H will be 65 vented through pipe 3 and trap I into the return main G, so that it will be withdrawn and vented, along with the air and non-condensi-

ble gases in return main G, through pipe 10 to the exhausting mechanism.

When operating at sub-atmospheric pressures, the check valves 6 and 26 in the vent pipes leading to the atmosphere will remain closed. By means of the equalizing connection provided through pipes 25, 29, one-way check valve 30 and air eliminator J, the same low pressure will be maintained above the water in tank T as exists in the return main G, so that water will flow freely thru horizontal leg 21 of return main G into the trap T. As long as the pressure differential between the supply and return mains is at or less than normal, that is represents a pressure equal to or less than the hydrostatic head of the water column in pipe 22, the condensate will gravitate into the boiler. Under these conditions the trap T does not function as such but is merely a part of the return conduit. If, however, due to excess of steam generated over condensation the normal differential is exceeded, and this condition persists, the liquid condensate will accumulate in the pipe 22 and trap T since the water column in the trap will be insufficient to balance the increased boiler pressure. This causes the float 28 to rise, closing the vent pipe 25 and opening the trap to the steam pipe 27 so that steam at boiler pressure enters the trap. Since boiler pressure is now exerted on the accumulated condensate, the water will gravitate into the boiler. During this operation, any condensate accumulating in the return main G above the trap T is prevented from escaping through the air vent of air-eliminator J by the float controlled valve of said eliminator (which is of the usual construction). Check valve 30 prevents water from flowing out through pipe 29 from the 90 eliminator J.

When the trap T has been discharged into the boiler, the float 28 will be lowered, thus closing steam pipe 27 and opening the vent pipe 25. The trap T is vented of excess pressure through pipe 25 and valve 26 to the atmosphere, the pressure in the trap being further reduced to that of the return main through equalizing pipe 29 and valve 30 leading to the air eliminator J.

With the exhausting mechanism out of action, and the system operating at normal or super-atmospheric pressures, the action of the return trap T will be the same as above described, although when the boiler pressure is not excessive and the trap T is not functioning, air will be vented from the return main G and trap T through the vent pipes 5 and 25 respectively. The higher pressure now existing in the return side of the system will permit the valves 6 and 26 to open so that this accumulated air may escape.

I am aware that return traps (such as shown at T) have heretofore been used in steam heating systems, for forcing liquid

condensate back to the boiler by steam pressure. However, I believe that I am the first to utilize one of these return traps, in the manner hereinabove set forth in a system operating under sub-atmospheric pressures. By means of the pressure equalizing and venting connections herein disclosed, the trap T may be utilized to return liquid condensate to the boiler under boiler pressure, without disturbing the low pressure conditions maintained in the return side of the heating system.

I claim:

1. In a steam heating apparatus, a steam generator including a boiler, a radiating system, means comprising an exhausting apparatus for maintaining a pressure below atmospheric in the radiating system and a difference of pressure between the inlet and outlet ends thereof sufficient to move the heating medium through the system, said exhausting apparatus operating to withdraw gaseous fluids only, and a conduit for liquid condensate through which water from the radiating system will gravitate to the boiler, a return trap in this conduit above the normal water level therein, and connections with this trap whereby steam at boiler pressure is utilized to return liquid to the boiler when this liquid accumulates in the trap.
2. In a steam heating apparatus, a steam generator including a boiler, a radiating system, means comprising an exhausting apparatus for maintaining a pressure below atmospheric in the radiating system and a difference of pressure between the inlet and outlet ends thereof sufficient to move the heating medium through the system, said exhausting apparatus operating to withdraw gaseous fluids only, and a conduit for liquid condensate through which water from the radiating system will gravitate to the boiler, a return trap in this conduit above the normal water level therein, and valved connections leading from the trap to the boiler and return main for alternatively admitting steam at boiler pressure to the trap or lowering the pressure in the trap to that of the low pressure side of the system.
3. In a steam heating apparatus, a steam generator including a boiler, a radiator, a supply main, a return main, exhausting means for withdrawing only air and non-condensable gases from the return main, a regulator for said exhausting means which tends to maintain a constant minimum pressure differential as between the supply and return mains, said return main comprising a standpipe connected with the lower portion of the boiler which extends above the water level of the boiler so as to provide for a water-column of a height to overbalance the boiler pressure when the difference in the pressures in the supply and return mains corresponds to or is less than the aforesaid differential, a return trap in the standpipe above the nor-

mal water level therein, and valved connections leading from the trap to the supply and return mains for alternatively admitting steam at boiler pressure to the trap or lowering the pressure in the trap to that existing in the return main.

4. In a steam heating apparatus, a steam generator including a boiler, a radiator, a supply main, a return main, exhausting means for withdrawing only air and non-condensable gases from the return main, a regulator for said exhausting means which tends to maintain a constant minimum pressure differential as between the supply and return mains, said return main comprising a standpipe connected with the lower portion of the boiler which extends above the water level of the boiler so as to provide for a water-column of a height to overbalance the boiler pressure when the difference in the pressures in the supply and return mains corresponds to or is less than the aforesaid differential, a check-valve opening toward the boiler in the connection between the standpipe and the boiler, a return trap in the standpipe above the normal water level therein, and valved connections leading from the trap to the supply and return mains for alternatively admitting steam at boiler pressure to the trap or lowering the pressure in the trap to that existing in the return main.

5. In a steam heating system, a steam generator, a radiator, supply and return pipes connecting the generator and radiator for respectively delivering steam to the radiator and returning liquid condensate to the generator, exhausting means connected with the return pipe for withdrawing air and non-condensable gases from the system and for maintaining a pressure differential between the supply and return sides of the system, a return trap positioned in the return pipe above the normal water level therein, and valved connections leading from the trap to the supply and return mains for alternatively admitting steam at boiler pressure to the trap, or lowering the pressure therein to the pressure existing in the return side of the system.

6. In a steam heating system, a steam generator, a radiator, supply and return pipes connecting the generator and radiator for respectively delivering steam to the radiator and returning liquid condensate to the generator, exhausting means connected with the return pipe for withdrawing air and non-condensable gases from the system and for maintaining a pressure differential between the supply and return sides of the system, a return trap positioned in the return pipe above the normal water level therein, a check-valve in the upper portion of the return pipe opening toward the trap, means for providing boiler-pressure in the trap when water accumulates therein, and means for venting

excess pressure from the trap when the water has been forced therefrom, said latter means including an equalizing pipe connecting the trap with the return main beyond the check-valve.

5 7. In a steam heating system, a steam generator, a radiator, supply and return pipes connecting the generator and radiator for respectively delivering steam to the radiator

10 and returning liquid condensate to the generator, exhausting means connected with the return pipe for withdrawing air and non-condensable gases from the system and for maintaining a pressure differential between

15 the supply and return sides of the system, a return trap positioned in the return pipe above the normal water level therein, a vent pipe leading from the trap, an outwardly opening check-valve in the vent pipe, a steam

20 pipe connecting the trap with the supply pipe, float-operated valves connecting the steam and vent pipes with the interior of the trap whereby the vent pipe will normally be open and the steam pipe closed, but the vent

25 will be closed and the steam pipe opened when liquid accumulates in the trap, a check-valve in the return pipe opening toward the trap, an equalizing pipe connecting the vent pipe with the return pipe beyond the check-valve therein, and a check-valve in the equalizing pipe opening toward the return pipe.

8. In a steam heating system, a steam generator, a radiator, supply and return pipes connecting the generator and radiator for

35 respectively delivering steam to the radiator and returning liquid condensate to the generator, exhausting means connected with the return pipe for withdrawing air and non-condensable gases from the system and for

40 maintaining a pressure differential between the supply and return sides of the system, a return trap positioned in the return pipe above the normal water level therein, a vent pipe leading from the trap, an outwardly opening check-valve in the vent pipe, a steam

45 pipe connecting the trap with the supply pipe, float-operated valves connecting the steam and vent pipes with the interior of the trap whereby the vent pipe will normally be open and the steam pipe closed, but the vent

50 will be closed and the steam pipe opened when liquid accumulates in the trap, an air-eliminator connected with the return pipe, a check-valve in the return pipe between the air

55 eliminator and trap and opening toward the trap, an equalizing pipe connecting the vent pipe with the air-eliminator, and a check-valve in the equalizing pipe opening toward the air-eliminator.

60 9. In a steam heating apparatus, a steam generator, a radiating system, means for maintaining a pressure below atmospheric in the radiating system and a determined difference of pressure between the inlet and outlet ends thereof, and a return conduit

through which water from the radiating system will gravitate to the generator, a return trap in this conduit above the normal water level therein, and means including a pipe connection with the generator and a float-controlled valve in the trap whereby steam at boiler pressure is utilized to return water to the generator when this water accumulates in the trap.

70 10. In a steam heating apparatus, a steam generator, a radiating system, means for maintaining a pressure below atmospheric in the radiating system and a determined difference of pressure between the inlet and outlet ends thereof, and a return conduit through which water from the radiating system will gravitate to the generator, a return trap in this conduit above the normal water level therein, and means comprising pipe connections with the generator and return conduit and float-controlled valves in the trap for alternatively admitting steam at boiler pressure to the trap or lowering the pressure in the trap to that of the low pressure side of the system.

75 11. In a steam heating apparatus, a steam generator, a radiator, supply and return pipes connected to the generator and radiator for respectively delivering steam to the radiator and returning condensate to the generator, means for maintaining a determined pressure differential between the supply and return sides of the system, a return trap positioned in the return pipe above the normal water level therein, and means comprising pipe connections with the generator and return conduit and float-controlled valves in the trap for alternatively admitting steam at boiler pressure to the trap, or lowering the pressure therein to the pressure existing in the return side of the system.

80 12. In a steam heating apparatus, a steam generator, a radiator, supply and return pipes connected to the generator and radiator for respectively delivering steam to the radiator and returning condensate to the generator, means for maintaining a determined pressure differential between the supply and return sides of the system, a return trap positioned in the return pipe above the normal water level therein, a check-valve in the upper portion of the return pipe opening toward the trap, means including a pipe connection with the generator and a float-controlled valve in the trap for providing boiler-pressure in the trap when water accumulates therein, and means for venting excess pressure from the trap when the water has been forced therefrom, said latter means including an equalizing pipe connecting the trap with the return main beyond the check-valve.

85 13. In a steam heating apparatus, a steam generator, a radiator, supply and return pipes connected to the generator and radiator for respectively delivering steam to the radiator

- and returning condensate to the generator, means for maintaining a determined pressure differential between the supply and return sides of the system, a return trap positioned in the return pipe above the normal water level therein, a vent-pipe leading from the trap, an outwardly opening check-valve in the vent-pipe, a steam pipe connecting the trap with the supply pipe, float-operated valves connecting the steam and vent pipes with the interior of the trap whereby the vent pipe will normally be open and the steam pipe closed, but the vent will be closed and the steam pipe opened when liquid accumulates in the trap, a check-valve in the return pipe opening toward the trap, an equalizing pipe connecting the vent pipe with the return pipe beyond the check-valve therein, and a check-valve in the equalizing pipe opening toward the return pipe.
14. In a steam heating system, a steam generator, a radiating system, means for controlling the flow of steam through the radiating system and maintaining a determined difference of pressure between the inlet and outlet ends thereof, and a return conduit through which water from the radiating system will gravitate to the generator, a return trap in this conduit above the normal water level therein, and means including a pipe connection with the generator and a float-controlled valve in the trap whereby steam at boiler pressure is utilized to return water to the generator when this water accumulates in the trap.
15. In a steam heating system, a steam generator, a radiating system, means for controlling the flow of steam through the radiating system and maintaining a determined difference of pressure between the inlet and outlet ends thereof, and a return conduit through which water from the radiating system will gravitate to the generator, a return trap in this conduit above the normal water level therein, and means including pipe connections with the generator and return conduit and float-controlled valves in the trap for alternatively admitting steam at boiler pressure to the trap or lowering the pressure in the trap to that of the low pressure side of the system.
16. In a steam heating system, a steam generator, a radiator, supply and return pipes connected to the generator and radiator for respectively delivering steam to the radiator and returning condensate to the generator, means in the supply pipe for controllably restricting the flow of steam to the radiator, means for maintaining a determined pressure differential between the supply and return sides of the system, a return trap positioned in the return pipe above the normal water level therein, and means including pipe connections with the generator and the return pipe and float-controlled valves in the trap for alternatively admitting steam at boiler pressure to the trap, or lowering the pressure therein to the pressure existing in the return side of the system.
17. In a steam heating system, a steam generator, a radiator, supply and return pipes connected to the generator and radiator for respectively delivering steam to the radiator and returning condensate to the generator, means in the supply pipe for controllably restricting the flow of steam to the radiator, means for maintaining a determined pressure differential between the supply and return sides of the system, a return trap positioned in the return pipe above the normal water level therein, a check-valve in the upper portion of the return pipe opening toward the trap, means including a pipe connection with the generator and a float-controlled valve in the trap for providing boiler-pressure in the trap when water accumulates therein, and means for venting excess pressure from the trap when the water has been forced therefrom, said latter means including a float-controlled valve in the trap and an equalizing pipe connecting the trap with the return main beyond the check-valve.
18. In a steam heating system, a steam generator, a radiator, supply and return pipes connected to the generator and radiator for respectively delivering steam to the radiator and returning condensate to the generator, means in the supply pipe for restricting the flow of steam to the radiator, means for maintaining a determined pressure differential between the supply and return sides of the system, a return trap positioned in the return pipe above the normal water level therein, a vent-pipe leading from the trap, an outwardly opening check-valve in the vent-pipe, a steam pipe connecting the trap with the supply pipe, float-operated valves connecting the steam and vent pipes with the interior of the trap whereby the vent pipe will normally be open and the steam pipe closed, but the vent will be closed and the steam pipe opened when liquid accumulates in the trap, a check-valve in the return pipe opening toward the trap, an equalizing pipe connecting the vent pipe with the return pipe beyond the check-valve therein, and a check-valve in the equalizing pipe opening toward the return pipe.
